ACOUSTICAL ASSEMBLY

John A. Chambers, Swampscott, Mass., assignor
to Johns-Manville Corporation, New York,
N. Y., a corporation of New York

Application June 19, 1940, Serial No. 341,221

14 Claims. (Cl. 20—4)

The present invention relates to acoustical assemblies, and particularly to assemblies including lighting units, the instant application being a continuation-in-part of my copending application Serial No. 293,713, filed September 7, 1939.

My previously filed application, Serial No. 293,713, is directed to the provision of an acoustical treatment employing a plurality of perforated facing elements with sound-absorbing pads therebehind, in combination with lighting fixtures incorporated in the treatment as a unitary part thereof.

The instant invention is concerned with a similar combination, in which, however, the acoustical treatment comprises a plurality of self-contained, integral, sound-absorbing panels. The invention is particularly concerned with and has for its principal object the provision of a suspension means for a ceiling or partition structure including acoustical units of the type referred to and lighting units comprising trough-like members containing illuminating devices such, for example, as the so-called "fluorescent" units. The latter comprise elongated glass tubes, the interior surfaces of which are coated with a material which will glow brightly or fluoresce in the presence of ultra-violet radiation produced in the tubes by means of a mercury vapor arc.

A further object of the invention is the provision of a partition or ceiling including a suspension means for the acoustical and lighting units as referred to above, which will adapt the partition for ready assembly and disassembly.

My invention will be more fully understood and further objects and advantages thereof will become apparent when reference is made to the more detailed description thereof which is to follow and to the accompanying drawings, in which:

Fig. 1 is a perspective view with parts broken away of a combined acoustical treatment and lighting means in accordance with the invention;

Fig. 2 is an enlarged sectional view taken on the line 2—2 of Fig. 1;

Fig. 3 is a perspective view of an acoustical unit as employed in the invention; and

Fig. 4 is a sectional view taken on the line 4—4 of Fig. 1.

Referring now to the drawings, and particularly to Figs. 1 and 2, there is shown an acoustical treatment or partition comprising a plurality of sound-absorbing panels 10 and lighting units 12. The sound-absorbing panels 10 (see particularly Fig. 3) may be of any of the types now conventional in the art composed of a porous,

self-sustaining, relatively rigid material and are preferably beveled at the corners of exposed edges. Each unit is provided along its edges with a slot or groove 13 approximately midway of its thickness. Above the grooves 13, the units 10 are recessed as at 15 to receive portions of the suspension means between adjacent units of the assembly without affecting the continuity of the exposed face of the treatment.

10 The lighting units 12, as previously referred to, comprise an inverted trough-like member 14 suitably formed of sheet metal or the like and may include end flanges 16 whereby a plurality of the members 14 may be secured together in 15 endwise abutting relationship by bolts, welding, or the like to extend the trough as illustrated particularly in Fig. 1. Each member 14 supports a lighting means of any suitable type which, however, preferably comprises an elongated glass tube 18 in which a mercury vapor arc may be produced to cause fluorescence of an inner coating to obtain fluorescent lighting of the type previously described. The tube is supported in the member 14 in any suitable manner and a casting 20 is provided for the electrical connections and other electrical elements of the lighting means which, per se, forms no part of the instant invention. The side walls of members 14 are retroverted to provide flanges 22, the flanges including preferably integral beads 24.

The suspension means for the lighting units and the acoustical units comprises a plurality of longitudinally extending, substantially parallel attaching members or T-bars 32 suspended from the inner ceiling or base 30 as by suspension members 34. The T-bars comprise a base 36 and resilient converging side flanges 38, including locking lips 40, and may be formed of any suitable, relatively light-gauge metal. The T-bars are spaced apart at intervals, depending upon the particular arrangement of lighting units and acoustical units desired. In the construction shown for the purposes of illustration, troughs 14 alternate with four rows of the acoustical panels 10. It will be understood, however, that any other suitable relationship between acoustical units and lighting units may be employed.

Bridging spaces which are to receive the acoustical units between the T-bars are members 42, suitably channel-shaped in cross section. As illustrated, the assembly of the T-bars, channel members 42 and suspension means 34 may be made by fastening the suspension means to the channel members 42 as by bolts 44 and securing the members 42 to the T-bars as by clips 46.

However, as will be understood, any other arrangement may be employed, for example, suspension means 34 may be secured directly to the bases 36 of the T-bars and channel members 42 may rest on the bases of the T-bars or be secured thereto, if desired. Channel members 42 support a runner 50, which, preferably, is in the form of an I-beam including horizontal flanges 52, by means of hangers or the like 54. Flanged, substantially L-shaped members 56, hereinafter referred to as L-members, including beads 58 in the vertical walls thereof, are inserted in the T-bars with their beads 58 in engagement with a lip 40 of the T-bar. L-members 56 and runners 50 preferably extend completely across the area to be treated. Inverted T-members 60 bridge the spaces between the L-members 56 and runner 50 with their ends resting on the flanges of said members.

In forming the assembly of the instant invention, after the T-bars, channel members 42, and runners 50 have been placed in position, either the trough members or the acoustical units may be initially installed. Assuming that the troughs are first to be positioned, these are placed between the T-bars and forced upwardly until the beaded flanges 22 are interlocked between the flanges 38 and lips 40 of the T-bars. L-members 56 are then similarly forced between the lips of the T-bars and the previously inserted flange of the trough-like members, with the flange of the L-member extending outwardly. A T-member 60, preferably having one of the flanges forming the head of the T removed, is placed to bridge between the member 56 and runner 50 adjacent a boundary of the area to be treated, with its flange extending inwardly. Two of the units 10 are then placed in position between the T-bar and runner 50, with the flanges of the members 56, 50 and 60 received in the respective edge slots 13. A filler strip 62 may be inserted to fill the slots in the contiguous edges of the units to prevent "breathing" between the units. A second T-member 60 is then placed in position, with a flange received in the outwardly facing slots of the previously installed units and the operations repeated. The units 10 are installed between the other T-bars and runners 50 in the same manner.

As previously pointed out, the above description and the drawings are directed to the preferred construction in which the troughs 14 are comparatively widely spaced. However, other arrangements may be employed. For example, only one or two rows of the acoustical units may be placed between the lighting units in any desired area, or for that matter a plurality of the lighting units may be placed side by side in certain areas. In any of these cases the T-bars are suitably arranged to support the lighting unit troughs in the desired locations. If but one or two rows of acoustical units are needed to fill the spaces between the T-bars, the runners 50 are not required and support for the units 10 is provided in the first case by L-members 56, although T-members 60 may also be employed to prevent breathing between the units, and in the second case by the L-members 56 and T-members 60. On the other hand, if the lighting units are to be very widely spaced, a plurality of the runners 50 may be required between the T-bars.

A construction in accordance with the invention as described above provides means for readily suspending an acoustical treatment including combined lighting units in any desired arrange-

ment. Also, the lighting units may be easily removed from time to time, as may be necessary for replacement and repair, merely by unsnapping the flanges 22 of the troughs from the

5 T-bars.

Having thus described my invention in rather full detail, it will be understood that these details need not be strictly adhered to, but that various changes and modifications will suggest 10 themselves to one skilled in the art, all falling within the scope of the invention as defined by the subjoined claims.

What I claim is:

1. A ceiling comprising a base, a plurality of 15 supporting bars suspended therefrom, said bars lying in substantial parallel relationship to one another, elongated lighting units carried by said bars and bridging certain of the spaces therebetween, means bridging others of the spaces between 20 said bars, and acoustical units supported from said bars and said means.

2. A ceiling comprising a base, a plurality of 25 supporting bars suspended therefrom, said bars lying in substantial parallel relationship to one another, elongated lighting units including flanges in interlocking engagement with said bars and bridging certain of the spaces therebetween, means bridging others of the spaces between 30 said bars, and acoustical units supported from said bars and said means.

3. A partition comprising a base, a plurality of 35 T-bars supported from said base and lying in substantial parallelism to one another, elongated lighting units including retroverted side flanges detachably interlocked in said T-bars and bridging certain of the spaces between said bars, members bridging others of the spaces between 40 said bars, and acoustical units supported from said T-bars and said members.

4. A partition comprising a base, a plurality of 45 T-bars supported from said base and lying in substantial parallelism to one another, said T-bars including opposed locking lips, elongated lighting units including retroverted side flanges having beads in removable interlocking engagement with said opposed interlocking lips of said 50 T-bars and bridging certain of the spaces therebetween, members bridging others of the spaces between said T-bars, and acoustical units supported from said T-bars and said members.

5. A partition comprising a base, a plurality of 55 T-bars supported from said base and lying in substantial parallelism to one another, elongated lighting units carried by said T-bars and bridging certain of the spaces therebetween, means cooperating with said T-bars and bridging others of the spaces therebetween, and members 60 carried by said T-bars and said means, respectively, for supporting acoustical units.

6. A partition comprising a base, a plurality of 65 T-bars supported from said base and lying in substantial parallelism to one another, elongated lighting units carried by said T-bars and bridging certain of the spaces therebetween, means 70 cooperating with said T-bars and bridging others of the spaces therebetween, flanged members carried by said T-bars and said means, respectively, and acoustical units including slotted edges with certain of the slots embracing the flanges of said members.

7. A partition comprising a base, a plurality of 75 T-bars supported from said base and lying in substantial parallelism to one another, elongated lighting units including retroverted side flanges detachably interlocked in said T-bars and bridg-

ing certain of the spaces between said T-bars, acoustical units spanning others of the spaces between said T-bars, and separate elements detachably carried by said T-bars for supporting adjacent edges of said units.

8. A partition comprising a base, a plurality of T-bars supported from said base and lying in substantial parallelism to one another, elongated lighting units including retroverted side flanges detachably interlocked in said T-bars and bridging certain of the spaces between said T-bars, acoustical units including slotted edges spanning others of the spaces between said T-bars, and elements detachably carried by said T-bars and including flanges received in certain of the slots of said units.

9. A partition comprising a base, a plurality of T-bars supported from said base and lying in substantial parallelism to one another, elongated lighting units including flanges interlocked with said T-bars and bridging certain of the spaces therebetween, means bridging others of the spaces between said T-bars, a flanged member supported from said means and extending parallel to said T-bars, flanged elements interlocked with said T-bars, and acoustic units including slotted edges with certain of the slots thereof receiving said flanges.

10. A partition comprising a base, a plurality of T-bars supported from said base and lying in substantial parallelism to one another, elongated lighting units including flanges interlocked with said T-bars and bridging certain of the spaces therebetween, means bridging others of the spaces between said T-bars, a flanged member supported from said means and extending parallel to said T-bars, flanged elements interlocked with said T-bars, and acoustical units including slotted edges with certain of the slots thereof receiving the flanges of said member and elements, and T-members extending at substantially right angles to said flanged member and T-bars and supported thereby, said T-members including flanges received in others of the slots of said acoustical units.

11. A partition comprising a base, a plurality of T-bars supported from said base and lying in substantial parallelism to one another, elongated lighting units including retroverted side flanges

detachably interlocked in said T-bars and bridging certain of the spaces therebetween, channels bridging others of the spaces between said T-bars, flanged runners extending substantially

5 parallel to said T-bars and supported from said channels, flanged elements including a portion received in said T-bars, acoustical units having slotted edges, a slot of an edge of certain of said acoustical units receiving the flanges of said flanged elements and a slot in the edge of others of said acoustical units receiving the flanges of said flanged runners, and a slotted edge of each acoustical unit receiving the flange of a flanged member extending between said runner and element.

10 15 12. A partition comprising a base, a plurality of spaced supports carried from said base, elongated lighting units carried by said supports and bridging certain of the spaces therebetween, means cooperating with said supports and bridging others of the spaces therebetween, and members carried by said supports and said means, respectively, for supporting acoustical units.

13. A partition comprising a base, a plurality of spaced supports carried from said base and each including resilient flanges defining a receiving slot, lighting units including retroverted side flanges detachably interlocked in the receiving slots of said supports and bridging certain of the spaces therebetween, acoustical units including slotted edges spanning others of the spaces between said supports, and elements detachably carried by said supports and including flanges received in certain of the slots of said acoustical units.

14. A partition comprising a base, a plurality of spaced supports carried from said base and each including resilient flanges defining a receiving slot, lighting units including retroverted side flanges detachably interlocked in the receiving slots of said supports and bridging certain of the spaces therebetween, acoustical units including slotted edges spanning others of the spaces between said supports, and elements having portions detachably interlocked in said receiving slots and including flanges received in certain of the slots of said acoustical units.

JOHN A. CHAMBERS.
